Inventor:
DAVID DAVIES,

Anthony Isina
His Attorney.

Patented Mar. 24, 1925.

UNITED STATES PATENT OFFICE.

DAVID DAVIES, OF CLEVELAND, OHIO, ASSIGNOR TO THE AMERICAN STEEL AND WIRE COMPANY OF NEW JERSEY, A CORPORATION OF NEW JERSEY.

LIFTING HOOK.

Application filed October 11, 1924. Serial No. 743,041.

To all whom it may concern:

Be it known that I, DAVID DAVIES, a citizen of the United States, and resident of Cleveland, in the county of Cuyahoga and State of Ohio, have invented certain new and useful Improvements in Lifting Hooks, of which the following is a specification.

This invention relates to lifting mechanism and more particularly to lifting hooks for lifting a plurality of coiled bundles of wire, rods or the like, and has for one of its objects the provision of such a mechanism which may be operated by the craneman at a distance to engage and hold a plurality of bundles of wire or the like, so as to facilitate the handling thereof.

Another object is to provide a hook of this class having the novel arrangement, combination, construction and design of parts hereinafter described and illustrated in the accompanying drawings.

Figure 1 is a side elevation of a lifting hook constructed in accordance with my invention, showing the hook supporting a plurality of hurdles of wire.

Figure 2 is a sectional elevation showing the means for locking the lifting element of the hook.

Referring more particularly to the drawings, the numeral 2 designates the rigid supporting bar or channel which is of such length as to extend across all the material being lifted. A mounting block or box 3 is secured to the upper face of the bar 2 intermediate the ends thereof.

A pair of U-shaped lifting hooks or arms 4 and 5 are provided for engaging the material to be lifted, and have the free ends of their upper legs pivotally mounted on pivot pins 6 and 7 which are secured in the opposite ends of the block 3, while their lower legs are free to enter through the hollow centers of the bundles of wire, rods, etc.

A lifting element in the form of a bar 8, terminating at its upper end in an eye 9 is adapted to be secured to the lifting cable 9^a of a crane or the like, and is connected to the arms or hooks 4 and 5 by a pair of links 10 and 11 which have their inner ends pivotally mounted on a pivot pin 12 mounted in a vertically disposed slot 13 in the bar 8, which slot permits a limited free movement of said bar relative to said pivot pin 12. The outer ends of the links 10 and 11 are pivotally connected as at 14 and 15, respec-

tively, intermediate the ends of the upper legs of the lifting hooks or arms 4 and 5, respectively.

The block 3 is provided with a centrally arranged depression or socket 16 which flares outwardly at its upper end as at 17 and is adapted to receive the lower end of the lifting element or bar 8.

Vertical movement of the lifting element or bar 8 relative to the block or box 3 will cause a swinging movement of the arms or hooks 4 and 5 about their pivot pins 6 and 7. When the element 8 is lowered the arms or hooks 4 and 5 will swing downwardly through an arcuate path, due to the connecting links 10 and 11, thereby causing their lower or free legs to move toward each other and pass within the hollow center of a row of coiled bundles of wire, rods or the like. When the element 8 is moved upwardly relative to the block or box 3, the arms or hooks 4 and 5 will swing upwardly and outwardly through an arcuate path, thus moving out of engagement with the material being handled.

A bell crank lever 20 is pivotally mounted on one side of the block 3 and has a counterweight 21 secured to one end and an operating cable 22 secured to its other end, which cable is adapted to be trained upwardly into position to be operated by the craneman or other operator.

A lock pin 23 has its one end pivotally mounted on a pivot pin 24 which is mounted in a slot 25 in the crank 20 and its other end mounted in an opening or aperture 26 which extends transversely through the box 3. The pin 23 is adapted to be reciprocated in the opening 26 by the rocking of the crank lever 20 about its pivot and to be moved through the opening 28 in the lifting element 8, so as to lock said element against movement relative to the block or box 3.

In operation the device is first lowered down onto a plurality of bundles of wire, rods or the like, which are arranged in rows of suitable size, until the supporting bar 2 rests on top of the bundles. Continued lowering of the lifting element 8 will then cause the arms 4 and 5 to swing downwardly and inwardly through an arcuate path and their free lower legs will enter through the hollow centers of the bundles of material. The lowering movement will be continued until after the hooks 4 and 5 have reached

their lowermost position, thus causing the lifting element 8 to enter the depression 16 and move relative to the pivot pin 12. When the lifting element 8 has reached its lowermost position, the operator will pull on the cable 22, thus rocking the bell crank lever 20 upwardly and forcing the locking pin 23 through the aperture 28 in the element 8. Tension will then be applied to the lifting element through the lifting cable 9^a and the load lifted. The weight of the material lifted will serve to prevent disengagement of the locking pin. When it is desired to release the load it will be lowered onto a fixed support or on the ground if desired, and the cable 9^a will be lowered so as to permit the lifting element to move down into the socket 16. As the tension is removed from the cable 9^a the counterweighted bell crank lever 20 will automatically withdraw the locking pin 23 from engagement with the lifting element 8. After the locking pin has been withdrawn the lifting element 8 will be moved upwardly so as to cause the arms 4 and 5 to swing outwardly and upwardly free of the load.

While I have shown and described only one specific form of my invention it will be understood that I do not wish to be limited thereto, since various modifications may be made without departing from the scope of my invention as defined in the appended claims.

I claim—

35 1. A lifting mechanism, comprising a rigid supporting member, a pair of substantially U-shaped material engaging arms having one end pivoted to said supporting member and their other end being adapted to engage the material to be lifted, a lifting element, a pair of links pivotally connected to said lifting element and said arms, whereby said arms are moved about their pivotal connections with said supporting member when said lifting element is moved vertically relative to said supporting member, means for locking said lifting element against vertical movement relative to said supporting member, and means for automatically releasing said locking means when the lifting strain is removed from said lifting element.

55 2. A lifting mechanism, comprising a supporting bar adapted to engage the material to be lifted, a mounting block secured to the upper face of said bar intermediate its ends, a pair of substantially U-shaped material engaging arms having one leg pivotally connected to said block and their other leg being adapted to engage the material to be lifted, a lifting element, and a pair of links having one end pivotally connected to said arms intermediate their ends and having their other ends pivotally connected to said lifting element, whereby said arms are moved about their pivotal connections with said mounting block when said lifting element is moved vertically relative to said mounting block, means for locking said lifting element against vertical movement relative to said supporting member, and means for automatically releasing said locking means.

60 65 3. A lifting mechanism, comprising a supporting bar adapted to engage the material to be lifted, a mounting block secured to the upper face of said bar intermediate its ends, a pair of substantially U-shaped material engaging arms having one leg pivotally connected to said block and their other leg being adapted to engage the material to be lifted, a lifting element, and a pair of links having one end pivotally connected to said arms intermediate their ends and having their other ends pivotally connected to said lifting element, whereby said arms are moved about their pivotal connections with said mounting block when said lifting element is moved vertically relative to said mounting block, means for locking said lifting element against vertical movement relative to said supporting member, and means for automatically releasing said locking means.

said mounting block when said lifting element is moved vertically relative to said mounting block.

3. A lifting mechanism, comprising a supporting bar adapted to engage the material to be lifted, a mounting block secured to the upper face of said bar intermediate its ends, a pair of substantially U-shaped material engaging arms having one leg pivotally connected to said block, and their other leg being adapted to engage the material to be lifted, a lifting element, a pair of links having one end pivotally connected to said arms intermediate their ends and having their other ends pivotally connected to said lifting element, whereby said arms are moved about their pivotal connection with said mounting block when said lifting element is moved vertically relative to said mounting block, and means for locking said lifting element against vertical movement relative to said mounting block.

4. A lifting mechanism, comprising a supporting bar adapted to engage the material to be lifted, a mounting block secured to the upper face of said bar intermediate its ends, a pair of substantially U-shaped material engaging arms having one leg pivotally connected to said block and their other leg being adapted to engage the material to be lifted, a lifting element, a pair of links having one end pivotally connected to said arms intermediate their ends and having their other ends pivotally connected to said lifting element, whereby said arms are moved about their pivotal connection with said mounting block when said lifting element is moved vertically relative to said mounting block, and means for locking said lifting element against vertical movement relative to said mounting block.

5. A lifting mechanism comprising a rigid supporting member, a pair of substantially U-shaped material engaging arms having one end pivoted to said supporting member and their other end being adapted to engage the material to be lifted, a lifting element, a pair of links having one end pivoted to said arms intermediate their ends and having their other ends pivotally connected to said lifting element at a point above said rigid supporting member, whereby said arms are moved about their pivotal connections with said mounting block when said lifting element is moved vertically relative to said mounting block, means for locking said lifting element against vertical movement relative to said supporting member, and means for automatically releasing said locking means.

6. A lifting mechanism, comprising a rigid supporting member, a pair of substantially U-shaped material engaging arms having one end pivoted to said supporting member

and their other end being adapted to engage the material to be lifted, a lifting element, a pair of links having one end pivoted to said arms intermediate their ends and having 5 their other ends pivotally connected to said lifting element at a point above said rigid supporting member, whereby said arms are moved about their pivotal connections with said mounting block when said lifting element is moved vertically relative to said

mounting block, means for locking said lifting element against vertical movement relative to said supporting member, and counter-weighted means for automatically releasing said locking means when the lifting strain 15 is removed from said lifting element.

In testimony whereof I have hereunto set my hand.

DAVID DAVIES.
